UNITED STATES PATENT OFFICE.

CHARLES A. TATUM, OF NEW YORK, N. Y., AND THEODORE B. OSBORNE AND THE FARMERS LOAN AND TRUST COMPANY, OF SAME PLACE, EXECUTORS OF FRANCIS M. UNDERHILL, DECEASED.

DESIGN FOR AN ATOMIZER-MOUNTING.

SPECIFICATION forming part of Design No. 31,466, dated August 29, 1899.

Application filed August 5, 1899. Serial No. 726,329. Term of patent 14 years.

To all whom it may concern:

Be it known that CHARLES A. TATUM, of New York, in the county and State of New York, and FRANCIS M. UNDERHILL, deceased, late of said city of New York, (THEODORE B. OSBORNE and THE FARMERS LOAN AND TRUST COMPANY, of New York, N. Y., the executors of the said FRANCIS M. UNDERHILL, appearing herein in behalf of the estate,) did invent and to produce a new and original Design for Atomizers, of which the following is a specification.

The design is represented in the accompanying drawing.

In the drawing, a is a head with the tapering portion b and the opening c. The lower part of the head is banded at d and has projecting therefrom the tubular bodies e f.

What is claimed is—

The design for an atomizer-mounting substantially as shown and described.

CHARLES A. TATUM.
